Patented Aug. 3, 1926.

UNITED STATES PATENT OFFICE.

CHARLES ADOLPHE ROSIER, OF NEW YORK, N. Y.

HYDROCARBON BURNER.

Application filed August 31, 1922. Serial No. 585,337.

This invention relates to hydrocarbon burners and the art or process of the employment of such burners in the burning of oils, particularly hydrocarbon oils, as fuel for heat generators.

One of the objects of this invention is to provide a hydrocarbon burner having means for regulating the radiation and reverberation of the hot gases from the furnace box 10 against the distillation and gasification chamber of the burner.

Another object of this invention is to provide a practical device of the character described in the form of a separate unit, which 15 may be readily installed and conveniently positioned on the furnace walls.

A still further object of the invention is to provide a device of the character described in which provision is made for facilitating 20 the atomization of the oil after distillation and gasification by the use of compressed air steam or the like vehicle.

Another object of this invention is to provide in a hydrocarbon burner, means for 25 effectively mixing the atomized gasified oil with compressed air or steam for obtaining efficient burning without the production of smoke.

A still further object of this invention is 30 to provide a device of the character described which is simple in construction, comparatively cheap to manufacture, and efficient in operation to a high degree.

Other objects of this invention will in 35 part be obvious and in part hereinafter pointed out.

The invention accordingly consists in the features of construction, combinations of elements and arrangement of parts which will 40 be exemplified in the construction herein-after described and of which the scope of application will be indicated in the following claims.

In the accompanying drawings, in which 45 is shown one of various possible illustrative embodiments of this invention,

Fig. 1 is a vertical section of a hydrocarbon burner, embodying this invention, dis-

posed in operative position on the furnace box, partially shown, of a heat generator; 50

Fig. 2 is a cross-sectional view thereof taken along line 2—2 of Fig. 1;

Fig. 3 is a detail cross-sectional view taken along line 3—3 of Fig. 1; and

Fig. 4 is a partial vertical section of a 55 modified form of the inlet apparatus adopted to enable the hydrocarbon burner to be more readily disassembled for removal from the furnace.

Referring in detail to the drawing, 10 indicates the furnace box of a heat generator such as a steam boiler (not shown) to which may be attached the hydrocarbon burner 11 by any suitable means such as the frame 12 enclosing the latter. 60

The hydrocarbon burner comprises, as is clear from Fig. 1, a portion 13 positioned adjacent the front of the furnace box 10 and a portion 14 disposed below the furnace box and adapted to communicate therewith by 70 means of the passage 15 provided in the bottom of the furnace box. The burner 11 comprises a tubular portion 16 divided into two compartments 17 and 18 by a baffle plate 19 extending longitudinally of the tubular portion 16, but somewhat shorter than the latter so as to provide at the far end thereof an opening or passage 20 for the purpose which will hereinafter become clear. The lower compartment 17 is adapted to distill the oil 75 and is provided at the front end 21 thereof with an opening 22 for the oil inlet pipe 23. The latter is connected to an oil storage tank (not shown) whereby the hydrocarbon oil may be supplied to the burner at any desired pressure. Suitable means for drawing off the residue of distillation is provided. In the form shown in the drawing, the lower compartment is tapped as at 24 for the discharge pipe 24^a which may be opened 80 and closed in any suitable manner. 85

The upper compartment 18 serves as the gasification chamber and is similarly provided with the opening 25 from which extends the outlet pipe 26 for leading the gaseified oil into the valve chamber 27, from 90 95

which it emerges through the valve opening 28 into the furnace box 10. The supply of gasified oil is controlled by means of the needle valve 29. The latter comprises the usual valve stem 30 having a hand wheel 31 at the extremity thereof and a valve head 32 operatively disposed adjacent the valve opening 28. Means are provided for injecting steam or compressed air for aiding in atomizing the gasified oil. For this purpose a valve 33 is inserted in the supply line 34 for the steam or compressed air. The valve 33 is of the usual construction having the valve head 35, and the hand wheel 36.

15 Below the valve 33, an annular chamber 37 is provided disposed adjacent the lower end 38 of the supply line 34 for receiving the steam or compressed air. The latter is then led through small openings or channels 39 around the valve chamber 27 leading through the opening 40 by means of the channels 41, so that an intimate mixture of the gasified oil and steam or compressed air is obtained upon emerging from the outlets 25 28 and 40. Before entering the furnace the atomized gas and steam, or compressed air enter the circular mixing chamber 42 where an intimate mixing of the gasified oil and compressed air or steam is obtained, and the 30 gasified oil is then further atomized so as to produce a highly efficient combustible mixture, which will burn without smoke. Orifices 43 for admitting air from the outside are provided in the mixing chamber for 35 starting the burner when no steam or air under pressure has yet been admitted. The supply of air may be regulated in any suitable manner, during continued operation of the burner as by means of a ring or sleeve 44 having ports 44^a which ring may be operated to close or open the orifices 43 thus securing proper combustion at all times.

40 It is clear that part of the heat of combustion, generated in the furnace, serves to heat up the distillation and gasification tube 16, particularly by reverberation through the passage 15. For effectively and positively controlling the temperature to which the oil is subjected during distillation and gasification, I provide the dampers 45, 46, disposed horizontally over the tube 16 between the latter and the passage 15. The dampers may be of any suitable design, preferably 45 50 arcuate in cross-section, as shown in the drawing, and when spaced from each other as shown in Fig. 2 to provide a variable opening 47 wherethrough heat from the furnace box is transmitted to or impinged on the distillation and gasification tube 16.

55 60 The said dampers 45, 46 extend respectively from the upper ends of the arms 48, 49, which are secured at their opposite ends respectively to the rock shafts 52, 53, having the operative handles 54, 55. The dampers

45, 46 may be moved toward or away from each other by rotating the rock shaft 52, 53, thus varying the size of the opening 47, and regulating the heating of the tube 16, as will be readily understood.

For starting the hydrocarbon burner, I provide the trough or basin 56 disposed below the distillation and gasification tube 16 and adapted to contain a suitable liquid fuel such as alcohol which is burned to supply the initial heat for raising the tube 16 to the required temperature for distilling and gasifying the oil.

The operation of the device will now be clear. The hydrocarbon oil is fed through the inlet 23 into the distillation and gasification tube 16, where it is heated to the required temperature. In the lower compartment 17, the oil is distilled so that volatile combustible ingredients of lower boiling points are separated from those of the higher boiling point oils, thus eliminating to a large degree the smoke producing elements. From the distillation compartment 17, the distillate passes through the passage 20 into the gasification compartment 18 and then into the atomizing chamber 42 through the valve 29 which regulates the supply of gaseous fuel to the furnace box. The steam or compressed air line is opened shortly after the burner has warmed up and as already explained is intimately mixed with the gaseous fuel before entering the furnace box. At the start the air orifices 43 are adjusted by means of the ring 44 for supplying the initial air to the furnace. After the burner 100 has been started, the outside air supply may be shut off or regulated to obtain the greatest heating effect. The dampers 45, 46 are also adjusted to provide the desired size of opening 47 for the radiant heat from the furnace box to the distillation and gasification chamber so as to obtain the maximum heating effect.

In Fig. 4 of the drawing a modified form of the burner is shown whereby the oil inlet portion of the burner may readily be disassembled and dismounted. In this form the distillation and gasification tube 16^a is a separate member which may be inserted through an opening in the supporting frame 12^a. The inlet 23^a, outlet 26^a, and exhaust 24^b are all in one piece or casting 56, which may be detachably mounted in operative relation to the tube 16^a. In the particular form shown in Fig. 4, this tube is provided with a flange 57 which is mitered as at 57^a to form a seat for the correspondingly mitered member 58 of the piece 56. A lug 59 extends from the frame 12^a and a screw bolt 60 extends through said lug with its head abutting against the piece 56 to secure it in position. The baffle plate 19 is secured at one end to the head of the piece 56 and

extends into the tube 16^a so that when the piece 56 is removed, the baffle is withdrawn together therewith.

Having thus described my invention, I 5 claim as new and desire to secure by Letters Patent:—

1. In an apparatus of the character described, the combination of a furnace adapted to burn a hydro-carbon fuel, a hydrocarbon oil burner therefor comprising a compartment, means in said compartment for distilling and gasifying the oil fuel supplied to said burner, said compartment having an opening therein in communication 10 with said furnace whereby the interior thereof may be heated from said furnace by reverberation of the heat thereof into said opening, and means for regulating the amount of heat reverberated through said 15 opening.
2. In an apparatus of the character described, the combination of a furnace adapted to burn a hydrocarbon fuel, a hydrocarbon oil burner therefor comprising a compartment, means in said compartment for distilling and gasifying the oil fuel supplied to said burner, said compartment having an opening therein in communication with said furnace whereby the interior thereof may be 20 heated from said furnace by reverberation of the heat thereof into said opening, and means for regulating the amount of heat reverberated through said opening, said regulating means comprising one or more 25 damper means disposed between said furnace and said compartment so as to vary the size of said opening.

3. In an apparatus of the character described, the combination of a furnace adapted to burn a hydrocarbon oil fuel, and a hydrocarbon oil burner therefor having a distillation and gasification chamber adapted to be heated by reverberation from said furnace, and means for regulating said heating of said distillation and gasification chamber, said means comprising one or more damper members disposed between said furnace and said chamber and means for opening and closing said dampers so as to regulate the amount of heat reverberated from 50 the furnace.

4. In an apparatus of the character described, the combination of a furnace adapted to burn a hydrocarbon fuel, a hydrocarbon oil burner therefor including a distillation and gasification chamber disposed so as to be heated by the latter by reverberation, an outlet from said chamber for the gasified oil, and an inlet in communication with said 55 outlet for supplying a fluid under pressure to mix with said gasified oil and atomize the latter.

5. In a hydrocarbon burner, a vaporization and expansion chamber, an atomizing chamber in communication with said first

mentioned chamber, means in communication with said atomizing chamber for supplying a fluid under pressure thereto for atomizing the vaporized oil therein and a mixing chamber in communication with said 70 atomizing chamber, and adjustable means connecting with the mixing chamber for admitting atmospheric air thereinto for mixing with the atomized fuel prior to combustion. 75

6. In a hydrocarbon burner, a support, a distillation and gasification chamber secured to said support, and having horizontal baffles extending from the forward end of said chamber longitudinally toward the rear thereof to divide the latter into a lower and upper compartment, said baffle being spaced from the rear end of the chamber so as to provide communication between the lower and upper compartments, an atomizing 80 chamber in communication with said upper compartment located above the latter, an injection chamber in communication with said atomizing chamber for injecting a fluid under pressure into the latter, and a mixing 85 chamber in communication with said atomizing chamber for receiving the atomized fuel therefrom.

7. The art or process of securing heat energy from a combustible fluid consisting in 90 exposing the fluid to heat, adjusting the intensity of the heat for vaporizing and expanding the fluid, atomizing the vaporous constituents thereof by a jet of other fluid under pressure, and then introducing and regulating an air supply to the resulting mixture prior to combustion. 95

8. The art or process of burning liquid hydrocarbons consisting in vaporizing and expanding said liquid hydrocarbons by heating same, passing the vaporous constituents thereof through a heated passage, adjusting the intensity of the heat of said passage, then atomizing said constituents by a jet of other fluid under pressure, and subsequently introducing and regulating an atmospheric air supply prior to combustion. 100

9. The art or process of securing heat energy from a combustible fluid which comprises simultaneously vaporizing and expanding the fluid by exposing same to heat, adjusting the intensity of the heat for controlling the vaporization and expansion of said fluid, atomizing the vaporous constituents thereof by a jet of other fluid under pressure, and then introducing and regulating an air supply to the resulting mixture prior to combustion. 110

10. The art or process of securing heat energy from a hydrocarbon liquid which comprises in vaporizing and expanding said liquid to a vapor, preheating the vapor by exposing same to heat, adjusting the intensity of the heat to precondition the hydrocarbon vapors for efficient combustion, mix- 120 125 130

ing the heated vapor constituents with a jet of other fluid, spraying the mixture, and subsequently introducing and regulating the atmospheric air supply.

- 5 11. In an apparatus of the character described, the combination of a furnace adapted to burn a hydrocarbon oil fuel, and a hydrocarbon oil burner therefor having a distillation and gasification element adapted
10 to be heated by reverberation from said fur-

nace, and means for regulating said heating of said distillation and gasification element, said means comprising one or more damper members disposed between said furnace and said element and means for opening and closing said dampers so as to regulate the amount of heat reverberated from the furnace.

15 In testimony whereof I affix my signature.
CHARLES ADOLPHE ROSIER.
